W. A. KNIPE.
INNERSOLE FOR ARCH SUPPORTING SHOES.
APPLICATION FILED JULY 8, 1921.

1,425,263.

Patented Aug. 8, 1922.

INVENTOR,
William A. Knipe,
of Marinette,
Wisc.

UNITED STATES PATENT OFFICE.

WILLIAM A. KNIPE, OF HAVERHILL, MASSACHUSETTS.

INNERSOLE FOR ARCH-SUPPORTING SHOES.

1,425,263.

Specification of Letters Patent. Patented Aug. 8, 1922.

Application filed July 8, 1921. Serial No. 483,197.

To all whom it may concern:

Be it known that I, WILLIAM A. KNIPE, a citizen of the United States, and a resident of Haverhill, county of Essex, State of Massachusetts, have invented an Improvement in Innersoles for Arch-Supporting Shoes, of which the following is a specification.

This invention relates to certain improvements in shoes which are provided with special means for supporting the arch of the foot, and more particularly to an arch supporting means which is incorporated in a shoe, as a part thereof, as distinguished from the type of arch supports which are adapted to be inserted and removed and which necessarily decrease the size of the shoe, so that a shoe, which is larger than would otherwise be necessary, must ordinarily be worn.

The object of my invention is to provide a shoe with means, which is incorporated therein, as a part thereof, which will provide an effective-support for the arch portion of the foot, without decreasing the size of the shoe, which is adapted to permit adjustment of the arch supporting portion according to the requirements of the wearer, and which will enable the shoe upper to be held closely to the arch portion of the foot and will relieve the strain thereon, so that the upper will not become stretched out of shape after the shoe has been worn for a considerable period.

I accomplish this object in the manner hereinafter described and as illustrated in the accompanying drawings in which:

Fig. 1 is a bottom plan view, partly broken away, of an inner sole embodying my invention.

Fig. 2 is a cross section at line 6—6 of Fig. 1.

Fig. 3 is a top plan view of another modified form of inner sole.

Fig. 4 is a cross section at line 8—8 of Fig. 3.

In the manufacture of a shoe embodying my invention, I employ an inner sole which is constructed according to the method disclosed in my Patent #1,144,420, of June 29, 1915, in which a double layer of canvas is attached to the under, or outer side of a leather inner sole by stitches which are located at a predetermined distance from the sole-edge, so that the edge-portion of the canvas may be turned up to the stitches,

to form the lip, to which the upper and welt are attached.

According to my invention I provide an inner sole section *a*, which is preferably of comparatively light weight leather, as thin flexible sole leather, the same being extended over the entire interior surface of the shoe bottom.

When said inner-sole section is cut out, it is formed to provide an extension *a'*, which projects transversely thereof, and continuously therewith, from its inner edge throughout its entire shank portion, the outline of said extension being made to correspond approximately to the outline of the arch-portion of the normal human foot, and said extension being skived to a thin edge.

The canvas layers *c* are attached to the under side of the inner sole by a row of stitches *d*, up to which the edge portion of the canvas is turned, to form the lip *c'*, to which the welt and upper are attached in the usual manner.

In order that the extension may more effectively perform its function as an arch-support, the inner line of stitches *d*, through the shank portion, is curved inward to a greater extent than is customary, so that the shank portion of the shoe is no wider than the corresponding portion of the normal human foot, and the surface of the extension *a'* may be considered as beginning approximately at the inner edge of the shank, with which the line of the stitches *d* correspond, as indicated in the drawing.

Before, however, the operation of attaching the canvas sections is performed, a reinforcing section *g* is arranged between the canvas layer *c* and the leather sole section *a*, said reinforcing section being preferably formed of relatively stiff sole-leather, as compared with that of which the sole-section *a* is formed, and being extended transversely of the latter throughout approximately its entire shank portion and arch engaging extension *a'*, the outer side edge of the reinforcing section being coincident with the outer edge of the section *a*, throughout the length of the shank portion, and its rear and front edges extending somewhat divergently from the outer edge, approximately at the lines of the heel breast and the ball respectively, as shown in Fig. 1. Said section *g* is termi-

nated at its inner edge at a short distance from the edge of the arch-engaging extension a' , the front, rear and inner side edge portions each being skived down to a thin edge, so that there will not be any abrupt shoulders formed in the sole section a , and, as the extension a' is also skived to a thin edge, when the inner sole is incorporated in the shoe the outline of the extension and 10 the portion of the reinforcing section beneath it, will not be defined through the upper.

The section g is placed in position between the canvas and the sole section a before they are stitched together, so that the stitches d pass through the section g also, and hold it securely in position. In practice the section g is adhesively connected to the section a before the stitching operation 20 is performed, so that it will be held in position while the canvas is placed in position on the sole and during the stitching operation permitting these operations to be as readily performed as if the section g 25 were not present.

The inner sole will thus be stiffened throughout its entire arch engaging portion without in any way stiffening the portions of the shoe which are bent in walking. 30 The shoe is manufactured in the customary manner, and, when finished, the sole-extension a' and reinforcing section g will be moulded by the last to fit closely against the entire arch portion of the foot, and 35 will lie against the inner surface of the adjacent portion of the upper. As the extension will be permanently shaped to fit closely against the arch and will be supported in this position by the reinforcing 40 section g , it will act to support the arch to some extent, and, to this extent, will relieve the pressure on the shoe upper when the latter is drawn up against it by the lacing, or other fastener. Moreover the 45 extension will afford a better distribution of the strain on the upper, in case the outward pressure of the foot against the extension is greater at one point than at another. The extension a' and reinforcing section g 50 are not attached to the upper, except through the lip c' so that an open pocket is formed between the same and the adjacent portion of the upper against which they normally lie, and in case it is desired that 55 the arch of the foot be supported to a greater extent than it would be with the extension and reinforce alone, a suitably shaped stiff metal plate, piece of felt, or some other suitable substance may be inserted in the pocket, thus formed, so that, 60 when the upper is drawn up by the lacing, the inserted substance will be pressed upward and inward against the reinforcing section, causing a correspondingly increased 65 pressure against the arch of the foot.

It is to be noted, in this connection, that it is important that the stitches which determine the position of the lip, to which the upper and welt are attached, at the inner side of the shank, be located at approximately 70 the line from which the arch portion of the human foot extends upward, or the inner outline of the shank, so that, when the upper is laced in position, the extension a' will be held up against the entire arch portion, and, 75 when the inserted plate, or felt, is employed, it may assist in pressing the arch portion of the foot upward from its lowest portion, so that the entire arch portion of the foot may be effectively supported. 80

An adjustable arch support may thus be incorporated in the shoe, as a permanent part thereof, without substantial additional expense, as compared with a shoe having an inserted support, so that it will be securely 85 held in position therein, and, at the same time, may be adjusted and readjusted practically as effectively as if it were removable. Also, the size of the shoe will not be reduced, to the extent that it would be with an insert- 90 able support.

If it should be desired to make the arch-engaging extension separate from the sole portion, the reinforcing piece may be employed to connect the same so that their surfaces will be continuous, as shown in Figs. 3 95 and 4.

In constructing the inner-sole in this manner, a sole section h of ordinary form and an extension piece i are provided, the latter being shaped to fit closely the inner shank edge of the sole. A reinforcing piece j' , of the same shape as the piece g , will be provided, and similarly arranged and connected to the extension piece by a row of stitches k , and 100 also, preferably, by an adhesive. In addition to the stitches for connecting the canvas under section to the sole, which, in this instance, also, will pass through the reinforcing piece, the latter may also be attached to 105 the sole adjacent its inner shank edge by another row of stitches between the stitches d and k , as shown in Fig. 8. 110

This construction is not thought to be as desirable as the form previously described 115 but is considered to be within the scope of my invention.

I claim:

1. An inner sole for welt shoes, comprising a bottom section having a downturned edge forming a lip to which the upper and welt are attached, a top section forming the interior covering for the shoe bottom, and a re-enforcing section disposed between said top and bottom sections at the shank portion thereof, said top and re-enforcing sections each being continuously extended transversely to a thin edge to form an arch-supporting portion, and said re-enforcing section being 125 skived to a thin edge at its front and rear 130

ends, and means for connecting all of said sections consisting of a row of stitches which pass therethrough from top to bottom at the base of said lip.

- 5 2. An inner sole for welt shoes, comprising a bottom section having a downturned edge forming a lip to which the upper and welt are attached, a top section forming the interior covering for the shoe bottom and a
- 10 re-enforcing section disposed between said top and bottom sections at the shank portion thereof, with its outer side-edge coincident with the outer side edge of the top section, and all of said sections being continuously
- 15 extended transversely to a thin edge, to form an arch-supporting portion and the front and rear ends of said reenforcing section being skived to a thin edge, and means for connecting said sections consisting of a row of
- 20 stitches which pass therethrough from top to bottom at the base of said lip.

3. An inner sole for welt shoes, comprising a bottom section having a downturned edge forming a lip to which the upper and welt are attached, a top section forming the 25 interior covering for the shoe bottom, and a re-enforcing section disposed between said top and bottom sections at the shank portion thereof, said top and re-enforcing sections each being continuously extended transversely 30 to a thin edge to form an arch-supporting portion, which lies against the shoe upper and is disconnected therefrom to provide a pocket between the upper and said supporting portions adapted to receive an auxiliary 35 supporting means, and means for connecting all of said sections consisting of a row of stitches which pass therethrough from top to bottom at the base of said lip.

In testimony whereof, I have signed my 40 name to this specification.

WILLIAM A. KNIPE.
